J. DARLING

MACHINE FOR CUTTING OPENINGS FOR FASTENERS IN METAL SHEETS
TO BE USED AS FORMS FOR MAKING CONCRETE FENCE POSTS

Filed Sept. 9, 1927

Inventor
JAY DARLING

By Lester L. Sargent

Attorney

UNITED STATES PATENT OFFICE.

JAY DARLING, OF WILLIAMSPORT, INDIANA.

MACHINE FOR CUTTING OPENINGS FOR FASTENERS IN METAL SHEETS TO BE USED AS FORMS FOR MAKING CONCRETE FENCEPOSTS.

Application filed September 9, 1927. Serial No. 218,544.

The object of my invention is to provide a novel and easily operating machine for cutting openings for fasteners in metal sheets to be used as forms for making concrete fence posts and which is especially adapted for cutting the peculiar type of openings required in the fence post forms which I have patented and which are used in producing the fence posts in which are embedded the peculiar type of fasteners devised and patented by me.

I attain the objects of my invention by the device illustrated in the accompanying drawings, in which—

15 Fig. 1 is a side elevation of my invention with a portion of same shown in longitudinal vertical section;

Fig. 2 is a section on line 2—2 of Fig. 1; and

20 Fig. 3 is a transverse section on line 3—3 of Fig. 1.

Like numerals designate like parts in each of the several views.

Referring to the accompanying drawings 25 I provide a base 1 having a channel 6 extending longitudinally of the base and directly under the perforated portions of the metal plate, as shown in Fig. 2. Mounted on base 1 is a sheet of metal 2 having round openings 3 and slots 4, the slots and round openings being successively arranged in close position to each other as shown in Figs. 1 and 2 of the drawings. The base 1 is cut out as indicated at 5 in appropriate shape to receive the 30 sheet of metal which is to be perforated before being shaped into the required form for making concrete fence posts. I provide a top member 7 fastened to the base 1 by a hinge 8 at one end and having a handle 12 35 at the other end. I provide a metal plate 9 affixed to top 7 and having a series of spaced bars 10 and posts 11 correspondingly positioned to the round openings 3 and slots 4 in the metal plate 2 of the base 1 to permit 40

45 said projections 10 and 11 to extend into the slots 3 and openings 4 when the top standing member 7 is brought down and the bars 10 and posts 11 are pressed through the metal sheet (not shown) which is inserted in the recessed portion 5 of the base 1 and perforated to receive the fasteners which are inserted in the forms before concrete is poured 50

whereby the fasteners are molded in the posts and may be readily withdrawn from the peculiar type of forms which I have patented.

The device is manually operated the sheet of metal being fitted into the recessed portion 5 of the base 1 and the upper member 7 brought down with sufficient force to stamp the perforations through the blank metal sheet as will be readily understood from the foregoing description and accompanying drawings.

What I claim is—

1. In a device for stamping perforations in sheet metal forms for making concrete posts, the combination of a base having a metal strip mounted thereon, said strip having perforations of the required shape to receive the desired type of fasteners, a channel extending longitudinally of the base and directly under the perforated portion of the metal plate, a top hinged to the base at one end, said top having a handle at the other end, and a metal plate affixed to the top, said plate having a series of projections corresponding in shape and position with the perforations in the metal plate carried on the base, the base also being suitably recessed to receive the sheet of metal to be perforated.

2. In a device for stamping perforations in sheet metal forms for making concrete posts, the combination of a base having a metal strip mounted thereon, said strip having perforations of the required shape to receive the desired type of fasteners, a channel extending longitudinally of the base and directly under the perforated portion of the metal plate, a top hinged to the base at one end, said top having a handle at the other end, and a metal plate affixed to the top, said plate having a series of projections corresponding in shape and position with the perforations in the metal plate carried on the base.

3. In a device for stamping perforations in sheet metal forms for making concrete posts, the combination of a base having a metal strip mounted thereon, said strip having perforations of the required shape to receive the desired type of fasteners, a channel extending longitudinally of the base and directly under the perforated portion of the

metal plate, a top hinged to the base at one end, an a metal plate affixed to the top, said plate having a series of projections corresponding in shape and position with the perforations in the metal plate carried on the base, the base also being suitably recessed to receive the sheet of metal to be perforated.

4. In a device for stamping perforations in sheet metal forms for making concrete posts, the combination of a base having a metal strip mounted thereon, said strip having a series of perforations consisting of slots and round openings in proximity to the slots successively arranged to receive the desired type of fasteners, a channel extending longitudinally of the base and directly under the perforated portion of the metal plate, a top hinged to the base at one end, and a metal plate affixed to the top, said plate having a series of projections corresponding in shape and position with the perforations in the metal plate carried on the base, the base also being suitably recessed

to receive the sheet of metal to be perforated.

5. In a device for stamping perforations in sheet metal forms for making concrete posts, the combination of a base having a metal strip mounted thereon, said strip having a series of perforations consisting of slots and round openings in proximity to the slots successively arranged to receive the desired type of fasteners, a channel extending longitudinally of the base and directly under the perforated portion of the metal plate, a top hinged to the base at one end, and a metal plate affixed to the top, said plate having a series of projections corresponding in shape and position with the perforations in the metal plate carried on the base, the base also being suitably recessed to receive the sheet of metal to be perforated, the base being recessed in the same tapering shape as the sheet of metal from which the form is to be made.

JAY DARLING.
